US00D593062S

(12) **United States Design Patent**
Lee et al.

(10) **Patent No.:** US D593,062 S
(45) **Date of Patent:** ** May 26, 2009

(54) **CELLULAR PHONE**

(75) Inventors: **Hye-Jeong Lee**, Seoul (KR); **Nam-Mi Kim**, Seoul (KR); **Chang-Soo Lee**, Incheon-si (KR)

(73) Assignee: **Samsung Electronics Co., Ltd.**, Suwon-Si (KR)

(**) Term: **14 Years**

(21) Appl. No.: **29/322,061**

(22) Filed: **Jul. 29, 2008**

(51) **LOC (9) Cl.** **14-03**

(52) **U.S. Cl.** ..... **D14/138 G**; D14/138 AD

(58) **Field of Classification Search** ..... D14/137, D14/138 R, 138 AA, 138 AB, 138 AC, 138 AD, D14/138 C, 138 G, 147, 191, 218, 247-248, D14/341-347, 455, 456, 496; D10/65, 78, D10/104; D13/168; D18/7; 455/556.1, 455/566, 575.1, 575.3; 345/169

See application file for complete search history.
